RADIORECEIVER

Robert P. Wuerfel, Ann Arbor, Mich., assignor
to International Research Corporation, Ann
Arbor, Mich., a corporation of Michigan

Application October 31, 1933, Serial No. 695,961

6 Claims. (CL 250—27)

This invention relates to a radio receiver, and particularly to a radio receiver in which the circuits and apparatus are so designed and assembled that the receiver will not only be highly efficient in operation but will be very compact.

A feature of the invention is the arrangement of circuits and tubes whereby each tube will perform several functions.

Another feature of the invention is the arrangement of circuits and tubes whereby only two electron tubes will perform the functions of a radio frequency amplifier, a detector, an audio frequency amplifier, a second audio frequency amplifier, and a rectifier.

Another feature of the invention is the circuit arrangement for the use of a tube which may be used to perform the functions of a rectifier and an audio frequency amplifier.

Another feature of the invention is the circuit arrangement whereby the receiver may be operated from alternating or direct current and the functions of the tubes will be the same in either case.

Another feature of the invention is the circuit arrangement for a tube which will permit it to operate as a radio frequency amplifier, a detector, and an audio frequency amplifier.

Another feature of this invention is the circuit arrangement which permits a tube which constitutes a regenerative detector, to be coupled directly to an antenna, but to be effectively isolated therefrom.

In designing radio receivers, it has heretofore been the general practice to employ a single tube for each function to be performed by a tube in the receiver. This not only requires a large number of tubes, but makes the assembled receiver bulky. It also increases the amount of wire necessary to connect the various elements of the receiver, and complicates the wiring.

In this invention the usual functions of several tubes in the ordinary radio receiver are combined in a single tube. The size of the assembled receiver is accordingly greatly reduced as compared with prior art practices, and the wiring is considerably simplified.

Referring to the drawings:

Fig. 1 is a circuit diagram of the receiver of my invention; and

Fig. 2 is an equivalent circuit diagram which will assist in explaining its operation.

In Fig. 1 an antenna 1 is connected to ground 2 through a coil 3 and a condenser 4. The coil 3 is the primary of a transformer 5 whose secondary 6 is connected across a tuning condenser 7. Ra-

dio signals received on the antenna 1 are impressed through the tuned circuit 6, 7, and a condenser 8 on a control grid 9 of an electronic tube 10. The control grid 9 is connected to ground through resistances 11, 12 and 13. The midpoint of resistances 11 and 12 is connected to ground through a condenser 14, and the midpoint of resistances 12 and 13 is connected to ground through a condenser 15. The tube 10 has a filamentary heater 16 and a cathode 17 which is grounded as shown, or through a resistor, with a condenser in parallel thereto, to provide a bias. The received radio signals are therefore impressed across the control grid 9 and cathode 17 which constitute one pair of input electrodes for this device. The tube 10 has also an anode 18 and screen grid 19. The screen grid is connected through a resistance 20 to the circuit which supplies plate potential to the plate 18 and is accordingly suitably biased. This screen grid is also connected to ground through a condenser 21. The plate 18 and cathode 17 constitute a pair of output electrodes for the tube 10 and are connected through a coil 22 and condenser 23. The input electrodes 9 and 17 and the output electrodes 18 and 17 with their associated circuits, constitute a radio frequency amplifier for the received radio signals.

Inductively coupled to the coil 22 is a second coil 23 which is in parallel with a second tuning condenser 24. One side of the tuning condenser 24 is connected to ground and the other side is connected through a condenser 25 and parallel grid leak 26 to a second grid 27 in the tube 10. The tuning circuit 23, 24, is therefore connected across the electrodes 27 and 17 and constitutes a second input circuit for the tube 10 for the amplified radio frequency currents in the output circuit between the electrodes 18 and 17. A second anode 28 is also enclosed in the tube 10. This anode is connected to the midpoint of resistances 12 and 13 through a condenser 29 and is connected to ground through a resistance 30 and condenser 31. The input electrodes 27 and 17 and output electrodes 28 and 17 and their associated circuits therefor constitute a detector for the amplified radio frequency currents.

Audio frequency currents in the output circuit of the detector whose output electrodes are 28 and 17 are now supplied through condenser 29 and resistances 12, 11, and 13 to the input electrodes 9 and 17 previously described. The input electrodes 9 and 17 and output electrodes 18 and 17 now act to amplify the detected audio frequency signals, so this same tube 10 again func-

tions, this time as an audio frequency amplifier. The coil 22 is connected to the anode 18 as previously described. The other side of this coil is connected through resistance 32 to condenser 31 and through condenser 33 and resistance 34 to the grid 37 of a second electron tube 53.

This electron tube has an anode 36, a grid 37, an anode 39, a filamentary heater 41 and two cathodes 38 and 40, and the tube functions in this circuit as an audio frequency amplifier and as a rectifier. The elements of the tube performing these two functions are physically separated within the tube with one filamentary heater 41 heating their respective cathodes 38 and 40.

The grid 37 is connected to ground through resistance 35 and condenser 46, and the cathode 38 is grounded. Grids 37 and cathode 38 constitute the input electrodes, and anode 36 and cathode 38 the output electrodes for the audio frequency amplifying portion of this tube. The audio frequency amplifying portion of tube 10 is coupled through resistances 32 and 35 and condenser 33 to the audio frequency amplifying portion of tube 53. Connected to anode 36 is a voice coil 48 for operating a loud speaker illustrated diagrammatically at 49, and the coil 48 is connected to ground through resistance 47 and condenser 31.

The rectifying function of this tube is performed by the anode 39 and cathode 40. The anode 39 is connected to one side 54 of a power line to which the circuit of the radio receiver may be connected by means of plug 52 which is adapted to fit an ordinary power outlet from the usual house circuit. The anode 39 is by-passed to ground by a condenser 50. The other side 55 of the power line is connected through a filter condenser 42 to the cathode 40. The cathode 40 is connected to ground through a second filter condenser 43. A resistance 44 is connected across the condensers 42 and 43 and the midpoint of this resistance is connected to condenser 46 through a resistance 45.

The filamentary heaters of tubes 10 and 53 are connected in series across the power line through a resistance 51. The circuit for these filamentary heaters is indicated near the bottom of Fig. 1 which shows that the circuit runs from the side 54 of the power line through resistance 51, and through filaments 16 and 41 in series to the other side 55 of the power line. Tube 53 may be comprised of two separate tubes, one containing elements 37, 36 and 38, and the other elements 39 and 40, in which case their heaters would be connected in series.

Condensers 14, 15 and resistance 12, comprise a radio frequency filter, which may be replaced by any other suitable form of radio frequency filter.

Condenser 54 and resistance 34 comprise a radio frequency filter to the grid 38 of tube 53.

Condenser 46, and resistor 45 form a hum or ripple filter to grid 37 of tube 53.

Condensers 42 and 43 with resistor 44 constitute the filter system which in Fig. 1 is shown in the negative side or negative leg of the circuit. This filter system may be placed in the positive leg of the plate supply circuit, if desired, as shown in my copending application Serial No. 652,812, filed January 21, 1933.

In the operation of the receiver the plug 52 will be inserted in a power socket. If the current is direct, the upper prong of the plug must make connection with the high potential side of the line. This may be determined by simply insert-

ing the plug and waiting for results, as no injury will be done if the plug is inserted with the upper prong connected to the low potential side. If the current is direct, a positive potential will be impressed on the anode 39, current will flow between the anode 39 and cathode 40, and positive potential will be impressed on the anode 36 through coil 48. If the current of the power circuit is alternating, an alternating potential will be impressed upon the anode 39 and will be rectified between the anode 39 and cathode 40, and in this event a direct current potential will also be impressed upon anode 36 through the coil 48. In either event the direct current from the rectifier having electrodes 39 and 40, will pass through the resistance 47 and a direct current potential will be impressed upon the anode 18 through resistance 32, upon the anode 28 through the resistance 30, and upon the screen grid 19 through resistance 20.

The operation of the circuit may be better understood by the equivalent circuit diagram shown in Fig. 2. In this figure the electrodes in the tubes and the associated circuits which perform the functions heretofore stated, are shown as though they were in separate tubes and the circuit elements repeated where necessary to indicate their functioning in the circuit. Thus it will be seen from this figure that the received radio signals are impressed upon input electrodes 9 and 17 of tube 10 across the tuning circuit 6, 7. The radio frequency currents are amplified in the tube and supplied inductively to the electrodes 27 and 17 of the same tube 10 across the tuned circuit 23, 24 through the condenser and associated grid leak 25, 26. Here the radio signals are detected and the output across electrodes 28, 17 is supplied through resistance coupling to the input electrodes 9 and 17 of tube 10, which this time function as part of an audio frequency amplifier. The output across electrodes 18 and 17 is supplied through resistance coupling to the input electrodes 31 and 38 of the second tube 53. The audio frequency currents are amplified in this tube and supplied to the voice coil in the output circuit across the electrodes 36 and 38. The power circuits will be clearly understood from the description in connection with Fig. 1, and need not be repeated here.

What is claimed is:

1. A radio receiver comprising an electron tube having a filamentary heater, a cathode, a grid, a screen grid, an anode, a second grid and a second anode, an antenna, a plurality of input circuits connected across said grids and cathode, a plurality of output circuits connected across said anodes and cathode, means for impressing radio signals from said antenna across said grid and cathode whereby said signals are repeated across said anode and cathode, means for impressing said repeated signals across said second grid and cathode whereby said signals are detected across said second anode and cathode, and means for impressing said detected signals across said grid and cathode whereby said detected signals are repeated across said anode and cathode.

2. A radio receiver comprising an electron tube having a filamentary heater, a cathode, a grid, a screen grid, an anode, a second grid and a second anode, an input circuit connecting said grid and cathode, an output circuit connecting said anode and cathode, means for impressing radio signals across said input circuit whereby said signals are amplified in said output circuit, a second input circuit across said second grid and cathode.

means for supplying said amplified signals to said second input circuit, a second output circuit across said second anode and cathode, means for detecting said signals and supplying said detected signals to said second output circuit, a third input circuit across said grid and cathode, means for supplying said detected signals to said third input circuit, a third output circuit across said anode and cathode, and means for amplifying said detected signals and supplying them to said third output circuit.

3. A radio receiver comprising an electron tube having a filamentary heater, a cathode, a grid, a screen grid, an anode, a second grid and a second anode, an input circuit connecting said grid and cathode, means for impressing radio signals on said circuit, an output circuit connecting said anode and cathode, means for amplifying said radio signals and supplying them to said output circuit, a second input circuit across said second grid and cathode, inductive means coupling said output circuit with said second input circuit, a second output circuit connecting said second anode and cathode, means for detecting said radio signals and supplying them to said second output circuit, a third input circuit connected to said grid and cathode, resistance means coupling said second output circuit with said third input circuit, a third output circuit connecting said anode and cathode, and means for amplifying said detected signals and supplying them to said third output circuit.

4. A radio receiver comprising an electron tube having a filamentary heater, a cathode, a grid, an anode, a second cathode, and a second anode, an input circuit connecting said grid and cathode, an output circuit connecting said anode and cathode, a second input circuit connecting said second cathode and second anode, a second output circuit connecting said second cathode and second anode, means for impressing audio frequency signals across said input circuit, means

for amplifying said signals and repeating them in said output circuit, means for impressing alternating current across said second input circuit, means for rectifying said current, means for impressing said rectified current on said second output circuit, a second electron tube in said receiver, input and output circuits for said second tube, and means for impressing said rectified current on said output circuit of said second tube.

5. A radio receiver comprising a first electron tube having a filamentary heater, a cathode, a grid, an anode, a second cathode, and a second anode, an input circuit connecting said grid and cathode, an output circuit connecting said anode and cathode, means for impressing audio frequency signals on said input circuit, means for amplifying said signals and repeating them in said output circuit, means for impressing alternating or direct current across said second cathode and second anode, a second output circuit across said second cathode and second anode, means for deriving direct current in said second output circuit, a second electron tube, input and output circuits for said tube, and means for supplying said direct current to said output circuits of said tubes.

6. A radio receiver comprising an electron tube having a plurality of electrodes, a filamentary heater for said tube, a plurality of input and output circuits connecting said electrodes, means for impressing radio signals on said tube, means for operating said tube as a radio frequency amplifier, a detector and an audio frequency amplifier, a second electron tube, a plurality of electrodes in said second tube, a filamentary heater for said second tube, means for operating said second tube as an audio frequency amplifier and as a rectifier, a power source, and means for connecting said filamentary heaters across said power source in series.

ROBERT P. WUERFEL.
